REEL STARTER

Louis A. Jurgensen and Bernard A. Martz, Kenora, Ontario, Canada, assignors to Minnesota and Ontario Paper Company, Minneapolis, Minn.

Application May 20, 1957, Serial No. 660,179

5 Claims. (Cl. 242—65)

This invention relates to a means for continuously winding rolls of material and has for an object to provide means for changing the winding material from a completed roll to a fresh roll without interruption in supply or change of speed in the winding material.

Many forms of machines are adaptable to produce and operate on a continuous web. Such machinery will naturally discharge the web in a continuous operation. In order that the web may be wound in practicable quantity upon separate reels it is necessary to discontinue the winding upon a reel which has received a predetermined quantity and to initiate winding upon an empty reel without stopping the continuous operation of the web producing or treating machinery. For example, in the paper industry a paper making machine produces a continuous web of paper and under ideal conditions a machine will not be shut down for several days. Similarly, paper coating machines are more efficiently run in a continuous manner and to this end paper may be supplied to them from a succession of reels which are so handled so as to splice the leading end of the uncoated paper to the trailing end of the spent reel. These splices may be made by any of the well known flying splice mechanisms and unless it is necessary to stop the machine for purpose of change of reels, the coating operation may be continuously performed in either of these examples as well as in any other instance. It is highly desirable to provide instantaneous transfer of the web from one winding reel to another.

Various types of reeling devices are known which are capable of handling a continuous moving web. One widely used form is known throughout the paper industry as the "Pope reel." Such a reel is shown in United States Patent No. 1,248,542. The present invention is particularly adaptable for use in conjunction with the Pope reel although, obviously, it is not limited in its use to such reel. For the purpose of description the invention will be set forth in connection with the Pope reel.

In general the Pope reel comprises a driving drum which is rotated at a peripheral speed equal to the speed of movement of the web with which it is to be used. Empty reels are placed into frictional contact with the surface of the driving drum and the leading end of the paper is secured in some manner to the empty reel whereby rotation of the driving drum will serve to rotate the empty reel and wind the paper therearound. When a predetermined quantity of paper has been wound upon the reel, it is necessary to shift the filled reel while it continues to wind to a position permitting the insertion of a new empty reel.

At this time the web is severed along a line just beyond the empty reel and the leading edge thus formed is directed upwardly around the empty reel. The directing of the web may be accomplished by the use of jets of air or water or steam, or may be accomplished by some mechanical manipulation or even by manual manipulation. Assuming a manual manipulation, the leading edge is gripped by the operators at opposite sides of the ma-

2

chine and thrown up and over the empty reel whereby the leading edge drops down upon the face of the paper progressing toward the reel. This serves to drag the leading edge into the nip between the winding reel and the driving drum and forms a bight having sufficient friction to secure the web to the winding reel. From this point on the web of paper will be progressively wound upon the reel.

At an appropriate time the partially wound reel may 10 be moved along the periphery in the direction of rotation thereof and brought to rest in a suitable bearing mechanism wherein it continues to wind in order to accumulate the predetermined quantity of web material. In the meantime a new empty reel is brought into position and 15 is suspended just above the driving drum in a position ahead of the reel upon which the web is being wound. When the predetermined quantity is reached, it is necessary to sever the web at a point between the empty reel and the filled reel and it is necessary to direct the leading edge of the web around the empty reel to initiate winding upon the same.

The usual steel roll used as empty reels has been replaced by a rubber covered roll. The rubber covered roll has many advantages among which is no scoring or 20 marking of reel drum surface. When the empty is lowered onto rotating reel drum, the friction often breaks the web. This web breaking results in considerable loss of paper.

Accordingly, it is an object of this invention to provide means for bringing the empty reel to substantially 30 the same peripheral speed as that of the driven reel drum.

Other and further objects of the invention and the advantages of the same will be pointed out hereinafter 35 and indicated in the appended claims or will be obvious to one skilled in the art upon understanding the present disclosure.

While one embodiment of the invention has been described in more or less detail to comply with the requirements of the statute, it is nevertheless desired that the detailed description be considered merely as illustrative and not as limiting.

In the drawing:

Figure 1 is a top plan view of the reel starter with 45 parts broken away;

Figure 2 is an end view of the invention with parts broken away; and

Figure 3 is a sectional view of a part of the winding drum.

Referring to the drawing, the reel drum 10 is suitably rotatably mounted on a shaft, such as indicated at 12, which extends from the opposite ends of the reel or driving drum 10. The driving drum 10 is rotated by driving shaft 12. This shaft 12 may be driven as shown in 50 Figure 2 of United States Patent 2,475,480 or by any other suitable driving means. A web of material 14, such as paper, is delivered from a web making machine, calendering or other treating apparatus and is then passed over the surface of the reel drum and wound upon a reel core 55 or winding roll 16, which may be similar to that shown in Patent No. 1,925,670, to form a reel of paper or the like. The reel core 16 having paper or other material wound thereon is, of course, suitably supported by reel arms 60, to maintain the circumference of the roll of paper 60 or other material being wound thereon in engagement with the surface of the reel drum 10 in accordance with more or less common practice as shown in United States Patent 1,923,670.

While one reel is being formed on reel bar 16, another 70 reel bar 18 is positioned above the paper web 14 and adjacent to reel drum 10 so that the reel bar or winding

roll 18 is clear of the reel drum 10 but supported through the reel bar bearing housing mounted on stub shafts 20, which extend from opposite ends of the reel bar 18. The reel bar bearing housings are supported by yokes 21 and held from rotating by guide sides 22 and 24 in the yokes 21. The yokes having sides 22 and 24 are suitably hinged to bring the reel bar 18 first in contact with the flat belt 26 and then the surface of reel drum 10 through gears cut on the yokes and driven through pinions 58. This is done in accordance with more or less common practice for example, as is shown in United States Patent 1,923,670.

The contact of the reel bar 18 with flat belt 26, which is being driven by reel drum 10, transfers rotation to reel bar 18 until reel bar 18 is rotating at the same peripheral speed as reel drum 10. The reel bar 18 is then brought in contact with the paper web 14 passing over reel drum 10 at some predetermined time. The web 14 is then transferred from the reel drum 10 to the reel bar 18 by some suitable means.

The remainder of the cycle consists of removing the completed reel formed on reel bar 16, transferring reel bar 18 from the yokes to reel arms 60 by rotating the yokes. The sides 24 of the yokes are suitably hinged to facilitate this transfer of the reel bar 18 from the yokes to the reel arms 60. The yokes are then returned to a suitable position to where another reel bar can be positioned into the yokes and the cycle repeated.

The reel drum 10 has a notch or groove 25 formed along one edge. This groove 25 is for the reception of a belt-like member 26. To insure that the belt remains in the groove 25, a stop member 27 is attached by suitable means 31 to the side of the reel drum.

Pulley 28 is fixed on cross member 33 in a suitable position to provide sufficient belt wrap of belt 26 on the reel bar 18 to provide for spinning the reel bar while still clear of the web 14. It is preferable, but not necessary, that the pulley 28 be adjustable in height above the reel drum 10 and this may be accomplished through the means of hand wheel 34 and stem 35, which is operatively connected to reel support members 30.

Frame members 54 which are connected to plate 56 have upwardly extending portions or ears 38 which support belt pulleys 36. The sides of frame member 54 have elongated openings 23 therein, which are adapted to slide blocks 50. Slide blocks 50 are bearing members for take-up pulley 40. To the blocks 50 is attached cable 42 by attaching member 48. The cable 42 passes over pulley 44 and has attached thereto weight 46. This arrangement provides for the variations in belt length during the starting cycle and also maintains a fixed tension on the belt 26 at all times.

What is claimed:

1. A web winding apparatus comprising a driving drum, means for rotating the driving drum, a winding roll normally disposed in contact with the driving drum, means for initially supporting the winding roll out of contact with the driving drum, a pulley positioned in a plane higher than the winding roll, a slidably mounted pulley, a weight attached to the slidably mounted pulley, and a belt passing over the slidably mounted pulley, the pulley positioned in a plane higher than the winding roll and the driving drum, said belt contacting the winding roll when in the initial position out of contact with the driving drum.

2. A web winding apparatus comprising a driving drum having a groove in the surface adjacent one edge, means for rotating the driving drum, a winding roll normally disposed in contact with the driving drum, means for initially supporting the winding roll out of contact with the driving drum, a pulley positioned in the plane higher than the driving drum, substantially parallel plates having elongated openings therein, slidable blocks slidably mounted in said openings, a movable pulley carried by the slidable blocks, a weight attached to the slidable blocks and a belt operatively mounted in the said groove on the driving drum, the pulley in the plane higher than the driving drum and the movable pulley, said belt contacting the winding roll when in the initial position out of contact with the driving drum to bring the winding roll up to the speed of the driving drum before the roll comes into contact with the surface of the driving drum.

3. A web winding apparatus comprising a driving drum, means for rotating the driving drum, a pulley mounted in a plane higher than the surface of the driving drum, a winding roll normally disposed in contact with the driving drum, means for initially supporting the winding roll out of contact with the driving drum, substantially parallel plates having elongated openings therein and pulley supporting ears, slidable blocks mounted in said openings, a movable pulley carried by said slidable blocks, a fixed pulley supported by said ears and a belt operatively mounted on the driving drum and the said pulleys, said belt contacting the winding roll in the initial position out of contact with the driving drum to bring the winding roll up to the speed of the driving drum before the roll comes into contact with the surface of the driving drum.

4. A web winding apparatus comprising a driving drum having a groove in the surface adjacent one edge, a stop member removably secured to the driving drum along the edge of the groove, means for rotating the driving drum, a rubber-covered winding roll normally disposed in contact with the driving drum, means for initially supporting the winding roll out of contact with the winding drum, a pulley positioned adjacent the winding drum and in a plane higher than the winding roll, a slidably mounted pulley, a weight attached to the slidably mounted pulley, a belt operatively mounted in the groove of the driving drum, and the said pulleys, said belt contacting the winding roll when in its initial position to bring the roll up to the speed of the winding drum.

5. A web winding apparatus comprising a driving drum, a means for rotating the driving drum, a winding roll normally disposed in contact with the driving drum, means for initially supporting the winding roll out of contact with the driving drum, a pulley positioned in a plane higher than the winding drum, a slidably mounted pulley, a belt passing over said pulleys and said driving drum, said belt contacting the winding roll when in the initial position out of contact with the driving drum, and means for urging the slidably mounted pulley in a predetermined direction whereby substantially constant tension is maintained upon the said belt.
